FRANK A. DIODATO, OF NORTH COLLINS, NEW YORK, ASSIGNOR TO DIO-KADS CORPORATION, OF BUFFALO, NEW YORK, A CORPORATION OF NEW YORK.

AUTOMATIC OR SAFETY TRAIN-STOP MECHANISM.

1,345,753.

Specification of Letters Patent.

Patented July 6, 1920.

Application filed August 25, 1919. Serial No. 319,533.

To all whom it may concern:

Be it known that I, FRANK A. DIODATO, a citizen of the United States of America, and resident of North Collins, Erie county,

5 State of New York, have invented certain new and useful Improvements in and Relating to Automatic or Safety Train-Stop Mechanisms, of which the following is a specification.

10 This invention relates to certain improvements in train stop mechanisms; and the objects and nature of the invention will be readily understood by those skilled in the art in the light of the following explanations of the accompanying drawings illustrating what I now believe to be the preferred mechanical expression or embodiment of the invention from among other forms, constructions and arrangements 15 within the spirit and scope thereof.

An object of the invention is to provide improved means for automatically stopping trains that attempt to pass visual signals set against them.

20 A further object of the invention is to provide in automatic train stop mechanisms, improved means for cutting off the steam supply to the engine cylinders without regard to whether or not the engineer's throttle mechanism is in operative condition and independently of such throttle mechanism.

25 A further object of the invention, is to provide in automatic train stop apparatus, improved means for coöperating with means carried by the engineer's cab to bring about 30 stopping of the train and to utilize visual signal apparatus now in use along rail tracks or way for automatically moving said improved means to and from operative or set 35 positions.

40 With these and other objects in view, my invention consists in certain novel features in construction, and in combinations and arrangements as more fully and particularly 45 set forth and specified hereinafter.

Referring to the accompanying drawings:—

Figure 1 diagrammatically illustrates, in side elevation, a locomotive and the railroad way equipped with apparatus in accordance with my invention.

40 Fig. 2 is a detail sectional view through a portion of the locomotive boiler disclosing certain features of the apparatus of my invention.

Fig. 3 diagrammatically illustrates in section a portion of the locomotive cab and certain apparatus arranged along the railroad way.

Figs. 4 and 5 are detail views.

In the drawings, I more or less diagrammatically illustrate a portion of a railroad way and track, a block signal arranged along said way, and a locomotive on the track. In the steam dome 1 of the locomotive boiler 2, I show a portion of the usual or any suitable main or pipe 3 through which steam from the boiler is supplied to the engine cylinders for propelling the locomotive. The steam inlet to this steam main is controlled in the ordinary, or any suitable manner, by the engineer through the medium of any suitable throttle mechanism comprising the throttle valve 4, the throttle lever in the engineer's cab and operative connections, such as 5. The throttle lever and the operative connections actuated thereby sometimes become inoperative for one reason or other, and furthermore it is not desirable to add auxiliary devices and attachments to the throttle lever or its connections that might interfere with the free use of the throttle lever by the engineer, and hence I provide independent means for cutting off the steam supply to the cylinders in the event that it becomes necessary to stop the train without regard to the engineer. To this end, I provide an annular upwardly facing valve seat 6 in the steam supply main 3 and a coöperating swinging emergency cut off valve 7 arranged in the main above said seat and normally held in upright 90 opened position but adapted to swing down onto the seat to close the main against passage of steam to the cylinders. The shaft 95 or stem 8 forming the axis on which the valve swings, is fixed thereto and controls the movements thereof and is suitably mounted in the main, and on one projecting end of said stem, at the exterior of the main, 100 is fixed a toothed wheel or sprocket 9.

A longitudinally movable slide rod 10 is movable through suitable guides or boxes 11 from a point within the engineer's cab to a position within the boiler and having operative connection with said sprocket. In the example illustrated, the inner end 10' of this slide rod rests on the sprocket and is formed with a longitudinal series of tooth forming slots or openings receiving teeth 110

of the sprocket and in effect forming a rack by which the sprocket can be rotated in either direction by reciprocation of the rod or can be held locked by the rod. A coiled 5 spring 12 constantly acts on the rod in a direction to slide the same rearwardly and hence operate the sprocket in a direction to close the valve 7, while the rear end of the rod within the cab is provided with any 10 suitable handle such as 13, accessible to the engineer, by which the rod can be forced forwardly against the tension of said spring to rotate the sprocket in a direction to swing the valve upwardly to opened position.

15 Suitable means are provided to normally hold this rod set against the tension of said spring and holding the emergency valve 7 in opened position. For instance, I show a portion of the rod within the cab formed 20 with a notch or stop shoulder 14 (Fig. 3), and locking means provided with a stop, bolt or dog 15 normally engaging said stop 14 of the rod and locking or holding the rod in such set position.

25 Suitable means are provided for normally maintaining the bolt 15 in locking position and whereby said bolt can be withdrawn to trip the rod 10 and permit its spring to move the rod on its emergency valve closing stroke. In the particular example illustrated, I show the bolt 15 carried by a slide embodying a body 16 from which the bolt 15 projects, and arms 17, 17', carried by and slidably in guides or boxes 18 carried 30 by the side wall of the cab and at their outer ends provided with anti-friction rollers 19. In this example, the arms 17, 17', are horizontal and parallel and spaced apart, one above the other, and these arms 35 extend from the interior of the cab with their outer ends projecting laterally from the right hand side of the cab. The body 16 is vertically arranged within the cab and is carried by said arms and arranged 40 at the inner ends thereof. The slide consisting of said body and said arms is yieldingly held in normal position with the arms projecting in normal position at the exterior of the cab and with the bolt locking 45 the rod 10 in normal position, by spring 20 which constantly exerts its tension to force the slide outwardly with respect to the cab side wall.

50 I also preferably provide means controlled by said slide 16 for applying the train brakes and sounding a whistle or other alarm, when the slide is forced inwardly by means arranged along the railroad way to operate rod 10 to shut off the steam to the 55 cylinders. In the example illustrated, I show the slide body 16 extended downwardly with its lower extremity extended laterally to form a free end finger 16' extending horizontally toward the adjacent 60 side wall of the cab. A weighted lever 21

is normally held in elevated position by this finger 16' through the medium of a ring or eye 21' carried by the free end of the lever and loosely receiving said finger. This lever forms the operating handle of a turn 70 plug, cock or valve 22 controlling an air escape pipe 23 through which air can be released from the train air brake system to cause application of the brakes to stop the train. When the lever 21 is in normal elevated position (Fig. 3) the valve 22 closes the pipe 23 against escape of air through said pipe from the air brake system so that said system is under the control of the engineer's valve 24 as usual. However, when the lever 21 is released it automatically drops and opens the valve 22 to permit brake applying escape of air through pipe 23.

75 The pipe 23 terminates and has its outlet in audible alarm or whistle 25 constructed and arranged to be loudly sounded by the escape of air through pipe 23. However, the escape of air to sound the whistle is controlled by a plug valve 26 in the outlet end of pipe 23. The projecting stem of 80 plug valve 26 is provided with handle 27 by which the valve can be manually opened and closed, and also with pinion 28 by which the valve can be opened and closed through the action of rack 29 carried and actuated 85 by piston 30 in cylinder 31. A branch air pipe 33 leads from air escape pipe 23 into said cylinder below the piston therein and this branch pipe is fitted with a plug valve 34 by which the flow of air therethrough 90 can be controlled. When the valve 22 is opened, the pressure enters the cylinder and elevates the piston and thereby opens valve 26 through the operation of the rack and pinion, and hence permits escape of air into 95 the whistle to apply the brakes. The piston and cylinder arrangement for opening the air escape from pipe 23 is designed to prevent a dangerously sudden application of 100 the train brakes which might occur should the air be allowed to suddenly escape on the opening of valve 22.

105 It will be understood, that when the slide 16 is forced inwardly to release the mechanism for closing the emergency steam cut off valve, the finger 16' moves rearwardly from the ring 21', and automatically releases the air brake applying emergency lever 21.

110 After the slide has been forced inwardly by the operation of the means along the railroad way, the spring 20 returns the slide to normal position. After the train has been brought to a stop, the engineer can elevate lever 21 to close the emergency air escape pipe 23, and hold the lever elevated by again inserting the finger 16' through the ring 21'. The engineer will then again open the steam main to control by the throttle valve, by forcing the rod 10 forwardly 115

against the tension of spring 12 until the bolt 15 drops into the notch 14 to lock the rod 10 in normal position.

Devices are arranged at suitable intervals 5 along the railroad way to engage and force the slide 16 of a passing locomotive inwardly to perform the functions hereinbefore described, when that locomotive attempts to enter a block that is not open or 10 to pass a signal set against the passage of such locomotive.

In the example illustrated, I show a block signal post or tower 33 in fixed position beside the track and carrying a vertically 15 swingable semaphore 34. Suitable mechanism is provided to operate the semaphore, for instance such as is in common use. In common practice, the semaphore is normally set against the passage of trains, as shown 20 in Fig. 3. If the two blocks ahead are empty so that a train is free to enter the first block the semaphore assumes vertical position. If the first block ahead is empty but a train is located in the second block ahead, 25 the semaphore moves to a position half way between the safety (vertical) position and the danger or horizontal position. The semaphore when at this half way position is also set against a train entering the first 30 block. I utilize this signal system in use, for automatically controlling means along the railroad way to actuate the slide 16 etc. projecting from the locomotive. In the example illustrated, the posts 33 are hollow 35 and each is equipped with a rigid hollow lateral arm or jib 35 extending toward the track and at its outer end terminating in a vertical portion. A housing 36 is fixed to and depends from the lower end of each jib 40 and this housing is open at its side facing the track. A cam or track block 37 for operating the slides 16 etc. of passing trains is arranged in this housing 36. This block is elongated in the direction of movement of 45 trains on the track and on its side or edge facing the track is formed with an elongated concaved track or runway 37' to receive the rollers 19. This trackway longitudinally inclines or curves from its high 50 center toward its opposite ends. This block is rigid with an upwardly extending shank 38 vertically slidable in the lower open end of the fixed jib 35. The block is also vertically 55 slideable in the housing 36 from lower position (Fig. 3) to operate the lower rod or arm 17 of the locomotive slide 16, to upper operative position to operatively engage the upper rod or arm 17' of the locomotive slide, and to its inoperative position at its limit of 60 upward movement.

Suitable means are provided for operating the cam block from the semaphore 34 and for determining the position of the cam block by the position of the semaphore. 65 For instance, I show the cam block and its

shank counterweighted through the medium of weight 40 vertically movable in post 33 and flexible connection 41 extending from said shank to said weight over suitable pulleys 42. The flexible connection extends upwardly and horizontally through the hollow jib and downwardly in the hollow post. The connection includes a sprocket chain 41' in mesh with a sprocket pinion 44 on the shaft of the semaphore. The arrangement 75 is such that the relative positions of the semaphore and cam block are fixed and so that when the semaphore has dropped to vertical safety position the cam block will be elevated to its limit and hence out of operative position with respect to the arms 17, 17', of the passing locomotives. If the semaphore is then raised to half way position, set against train passage, the cam block will be automatically lowered and held in position with its track in the path of movement of the arm 17' of a passing train. If for any reason such train attempts to pass the signal, the arm 17' of its locomotive slide will engage and ride up on the cam track of 80 said block and the slide will be automatically forced inwardly to release the various means to bring the train to a stop. If the semaphore be moved to horizontal position, the cam block will be automatically moved 85 to its lowest position and the track of the block will be in position to operatively engage the lower arm 17 of the locomotive slide.

It is evident that various changes, modifications and variations might be resorted to without departing from the spirit and scope of my invention and hence I do not wish to limit myself to the exact disclosures hereof.

What I claim is:—

1. In train stop mechanism, a locomotive having an emergency steam cut-off valve for stopping the supply of steam to the locomotive cylinders, a spring actuated rod having operative connection with said valve for holding the same open and for moving the same to opened and closed positions, a bolt engaging said rod to lock the latter against valve closing movement, and slides operatively connected with said bolt projecting to 100 the exterior of the locomotive, one or the other of said slides being adapted to be moved longitudinally by means located along the railroad way whenever said means are in various danger positions, whereby said 105 bolt will release said rod and permit valve closing movement thereof.

2. In train stop mechanism, a locomotive having an emergency steam cut off valve for stopping the supply of steam to the locomotive cylinders, a spring-held rod having operative connection with said valve for holding the same open and for moving the same to opened and closed positions, and a slide having a bolt engaging said rod to lock the 115 120 125 130

latter against valve closing movement, said slide projecting to the exterior of the locomotive and adapted to be moved longitudinally by means located along the railroad way to release said rod and permit valve closing movement thereof.

3. In train stop mechanism, a locomotive having an air brake air release pipe, a whistle on the discharge end of said pipe, a valve controlling escape of air to the whistle, a cylinder having a piston operatively connected to said valve for opening the same, a valved branch pipe from said air release pipe to said cylinder, a valve controlling flow of air from the brake system through said air release pipe, means constantly tending to open said last mentioned valve, and devices acting on said means to hold said valve closed, said devices arranged to be operated by means along the railroad way to release said means in case of emergency and permit opening of the valve controlled thereby.

4. In train stop mechanism, a visual signal arranged along the railroad way and movable to and from train passage and train stop positions, a contact block, suspending means for said contact block operatively connected with said visual signal whereby said suspending means are automatically raised and lowered by and with said signal, to support said contact block at various elevations, said contact block when suspended at its various elevations being either in inoperative or operative position relative to means on a passing locomotive adapted to be actuated by said block to stop the locomotive.

5. In train stop mechanism, a visual signal arranged along the railroad way and movable to and from train passage and train stop positions, a contact block, suspending means for said contact block operatively connected with said visual signal whereby said suspending means are automatically raised and lowered by and with said signal, to support said contact block at various elevations, said contact block when suspended at its various elevations being either in inoperative or operative position relative to means on a passing locomotive

adapted to be actuated by said block to stop the locomotive, said visual signal, contact block, and their connections, being so arranged that the contact block will be suspended at inoperative position when the signal is at train passage position, and will be suspended in operative position when the signal is at train stop position.

6. In train stop mechanism, a visual signal pivotally arranged along the railroad way and movable to and from train passage and train stop positions, a contact block, a flexible connection secured to said contact block and including a sprocket chain, the pivotal means of said visual signal having a sprocket pinion thereon in operative engagement with said sprocket chain whereby said flexible connection is moved by and with the pivotal movement of said signal to move said contact block to operative position to operate means on a passing locomotive to automatically stop the same when said signal is moved to train stop position, and said flexible connection is moved in the reverse direction to reversely move said block to inoperative position when the signal is moved to train passage position.

7. In train stop mechanism, a hollow mast, a visual signal pivotally arranged thereon and movable to and from train passage and train stop positions, a hollow lateral arm projecting from said mast and terminating in a hollow downward extension having an opening arranged adjacent the railroad way, a flexible connection in said mast, lateral arm, and downward extension passing over suitable pulleys, a contact block at one end of said flexible connection and positioned in said opening, and a counter weight at the opposite end of said flexible connection and in said hollow mast, the pivotal means for said visual signal having operative connection with said flexible connection whereby the latter is moved by and with said signal to raise or lower said contact block into inoperative or operative position to operate means on a passing locomotive to automatically stop the same as said signal is moved to train passage or train stop position.

FRANK A. DIODATO.
